UNITED STATES PATENT OFFICE.

JOSEPH L. MORAHAN, OF JACKSON, MISSISSIPPI.

HAT BLOCKING, FLANGING, AND FINISHING APPARATUS.

Application filed March 2, 1925. Serial No. 12,668.

To all whom it may concern:

Be it known that I, JOSEPH L. MORAHAN, a citizen of the United States, residing at Jackson, in the county of Hinds and State of Mississippi, have invented certain new and useful Improvements in Hat Blocking, Flanging, and Finishing Apparatus, of which the following is a specification.

This invention relates to an apparatus for blocking, flanging and finishing hats and has for one of its objects to provide a machine of this character which will be simple in construction, comparatively inexpensive to manufacture and install and more efficient in use than those which have been heretofore proposed. With the above and other objects in view which will appear as the description proceeds, the invention consists in the novel details of construction and combinations of parts more fully and herein-after described and particularly pointed out in the appended claims.

Referring to the accompanying drawings, forming a part of this specification in which like reference characters designate like parts in all the views;

Figure 1, is a side elevational view of a complete apparatus constructed in accordance with the present invention;

Fig. 2 is a top plan view on an enlarged scale of one of the blocking, flanging and finishing portions of the apparatus;

Fig. 3 is a top plan view of a sand bag or pressure member which is employed in connection with the apparatus; and,

Fig. 4 is an enlarged vertical sectional view through that portion of the machine illustrated in Fig. 2.

Referring more particularly to the said drawings, the numeral 10 indicates any suitable support such for example, the top of a table or bench, upon which is mounted by suitable legs 11, a steam drum 12 which may be supplied with steam through a pipe 13 from any suitable source, not shown. The said drum in turn supplies steam to a blocking, flanging and finishing device located at either end thereof and since these devices are duplicates of one another in substantially every respect, only one of them will be described in detail, the corresponding parts of the other device being designated by corresponding primed reference characters.

The blocking, flanging and finishing por-

tion of the apparatus comprises a suitable support or tripod 15 mounted upon the base or supporting member 10 upon the upper surface of which rests a hollow oval ring member 16. The said member, which may be composed of two parts 17 and 18, is shaped in cross section substantially as shown in Fig. 4 and steam from the drum 12 may be supplied thereto through the steam pipe 19 which is controlled by the valve 20 as is clearly shown in Figs. 1 and 4. An outlet pipe 21 having a control valve 22 leads from the opposite side of the member as is also clearly shown in the said figures. The member 18 is further provided with a plurality of slits or openings 23 in its upper surface through which the steam may be directed against the brim of the hat as will appear more fully below.

The supporting member 10 is provided directly below the member 16 just described and in axial alignment with the center thereof with a flanged bearing member 25 in which is slidably and rotatably mounted, a hollow shaft 26 which carries rigidly secured thereto a worm wheel 27 which is adapted to engage and disengage a worm 28 mounted upon a horizontally disposed shaft 29, journaled in suitable bearings 30 and adapted to be driven by a belt or chain 31 from any suitable source of power, not shown. Splined in the said hollow shaft 26 as by the key 32 is the stub shaft 33 which carries at its upper end the laterally projecting finishing arm 34 which is provided with the horizontally slidably angular projection 35 mounted upon suitable guides or pins 36 and normally pressed inwardly to the position shown in Fig. 4, by suitable springs 37. The members 34 and 35 are provided with cloth or felt pads 38 and 39 respectively which are adapted to engage the surface of a hat, as will appear more fully below. These pads may, if desired, be provided with suitable means for heating the same, such for example, as an electric resistance coil supplied with current from wires passing upwardly through the hollow shaft 26 and stub shaft 33.

As above stated, the shaft 26 is slidably mounted in the bearing 25 and the lower extremity or cap 40 of the said shaft is provided with a suitable latch or hook 41 adapted to engage a keeper 42 carried by the bearing member 25 whereby the shaft may

be maintained in its raised position shown in Fig. 4. On the other hand when it is desired to remove the hat from the machine, upon disengagement of the latch member 41 from said keeper, the shaft 26 and its associated parts may be dropped as indicated at the right hand of Fig. 1.

The numeral 45 indicates generally, a heating and pressure member to be applied 10 to the brim of the hat which is here shown as comprising an oval metallic ring member 46 to which is secured as by the clamping rings 47, engaging grooves 48 therein, a fabric bag member 49 which is preferably 15 filled with granular matter 50, such for example, as sand. These members 45, are adapted to be heated by placing them upon the steam drum, as indicated at the right of Fig. 1. Suitable handling means is provided, such as the rope 51, fastened to the bale 52 passing through a sheave or pulley 53 carried by an upright arm 54.

For heating and moistening the crown of the hat, there is provided a steam spray nozzle 55 connected by a suitable swivel connection 56 to a pipe 57, constituting a branch of the pipe 19.

For driving the worm shaft 29' of the duplicate apparatus, a belt or chain 60 may 30 be provided, extending from the shaft 29, as is clearly shown in Fig. 1.

In cleaning, blocking, flanging and finishing a hat, the procedure will be substantially as follows:

35 A member 16, of the proper size is first positioned upon the tripod 15 and a felt covering member 58 is placed thereon, see Fig. 4. The hat is next placed on a regular wooden block of the proper size, the sweat band being turned outwardly. The hat and block are then inverted and placed within the oval member 16 as indicated in broken lines in Fig. 4, and the steam turned on by means of the valve 20. The said steam will, 40 of course, fill the interior of the flanging member 16 and will escape therefrom, through the slits or openings, 23, thereby heating and softening the brim of the hat. In the meantime, the spray nozzle 55 has 45 been swung on its swivel connection to a position directly below the crown of the hat as indicated at the right hand of Fig. 1, and the steam issuing therefrom serves to heat and soften that portion of the hat. When 50 the steam treatment has been continued for a sufficient period, the steam may be turned off, the nozzle 55 swung out of the way, whereupon the finishing arm 34 is moved up into contact with the hat crown as shown in Fig. 55 4, by manually sliding the hollow shaft 26 and its associated parts upwardly in the bearing 25 and engaging the ring 41 with the keeper 42. This movement will bring the worm wheel 27 into engagement with the 60 teeth of the worm 28 and as power is now

supplied to the shaft 29 from the source not shown, the shaft 26 and the finishing arm 34 together with the vertical extension 35 will be rotated to cause the said arm to smooth and shape the crown of the hat to the wooden 70 block. After the said crown has been completely shaped, the power may be shut off and the finishing arm dropped back to its initial position, whereupon the sand bag member 45 may be removed and the hat and 75 supporting block taken from the apparatus.

While one form of the invention has been illustrated and described, it is obvious that those skilled in the art may vary the details of construction as well as the arrangement of 80 parts without departing from the spirit of the invention, and therefore, I do not wish to be limited to the above disclosure except as may be required by the claims.

What I claim is:

1. In an apparatus of the class described a hollow supporting member adapted to receive and support a hat with the brim resting thereon, said member being provided with steam discharge openings; means for supplying steam to the crown of the hat; a vertically movable shaft, provided with a finishing arm adapted to engage said crown, and to smooth and finish the same; a worm and means for driving the same; and a worm wheel carried by said shaft, adapted to be moved into and out of engagement with said worm.

2. A finishing mechanism for hats comprising an axially adjustable hollow shaft; 100 a stub shaft splined within said hollow shaft; a radially extending finishing arm rigid with said stub shaft; a yieldable angular extension carried by said arm; and means for rotating said hollow shaft.

3. A finishing mechanism for hats comprising an axially adjustable hollow shaft; 105 a stub shaft splined within said hollow shaft; a radially extending finishing arm rigid with said stub shaft; a yieldable angular extension carried by said arm; a worm and means for driving the same; and a worm wheel carried by said hollow shaft, adapted to be engaged and disengaged with said worm by axial movement of said shaft.

4. A finishing mechanism for hats comprising an axially adjustable hollow shaft; a stub shaft splined within said hollow shaft; a radially extending finishing arm rigid with 110 said stub shaft; a yieldable angular extension carried by said arm; a spring interposed between said arm and said hollow shaft; a worm and means for driving the same; a worm wheel carried by said hollow shaft, adapted to be engaged and disengaged with said worm by axial movement of said shaft; and means for holding said hollow shaft in position with said worm wheel in engagement with said worm.

JOE L. MORAHAN.
